METHOD OF MOUNTING A CUTTER UPON
EARTH BORING BITSRobert G. Peter, Houston, Tex., assignor to Reed
Roller Bit Company, Houston, Tex., a corpora-
tion of Texas

Application July 30, 1949, Serial No. 107,798

4 Claims. (Cl. 76—108)

1

This invention relates to new and useful improvements in methods of and means for mounting a cutter upon an earth boring drill bit and relates particularly to rock bit cutters of the cone-type.

In certain types of drilling, a relatively slow rotary speed of the drill pipe and bit is employed with the result that the bearing mounting for the usual bit cutter must be of sufficient strength to withstand the severe impact loads and the axial thrusts occasioned by such drilling. Because the speed of rotation is relatively slow, the frictional characteristics of the bearing are not too important as would be the case where high drilling speeds are employed.

It is, therefore, one object of this invention to provide an improved method of and means for mounting a rotatable cutter on its journal pin or shaft whereby an exceptionally rugged bearing arrangement capable of withstanding extreme axial thrusts and impact is produced.

An important object of the invention is to provide an improved method of mounting cone-type drilling cutters wherein the bore of the cutter is formed with a recess and wherein a portion of the journal pin or shaft on which the cutter is mounted is adapted to be deformed or displaced outwardly into the recess to thereby provide an annular bearing surface which retains the cutter upon the shaft and which also functions to carry axial thrust loads.

Still another object is to provide an improved method which consists in heating a section of a journal shaft or pin for roller cutters, inserting the shaft within the bore of a cutter and then applying sufficient force, either continuous or alternate, to deform the heated section of said shaft into a bearing recess in the wall of the bore of the cutter, whereby a bearing connection which prevents displacement of the cutter from the shaft is produced.

A still further object is to provide an improved mounting for cone-type rock bit cutters wherein the bore of the bit is formed with an annular recess which is adapted to coact with an annular projection or ring portion which is provided on the journal pin or shaft upon which the cutter is mounted, said annular projection coacting with the recess to provide a bearing and also to prevent displacement of the cutter from said shaft.

Other and further objects of the invention will appear from the description of the invention.

In the accompanying drawings, which form a part of the instant specification, which are to

2

be read in conjunction therewith and wherein like reference numerals are used to indicate like parts in the various views:

Figure 1 is a view partly in section and partly in elevation of a cone type bit illustrating the improved cutter mounting constructed in accordance with the invention.

Figure 2 is a vertical sectional view of one section of the bit and illustrating the first step in the method of mounting the cutter.

Figure 3 is a view similar to Figure 2 showing the cutter placed upon the journal pin or shaft, and

Figure 4 is a view similar to Figures 2 and 3 illustrating the completed assembly.

In the drawings, the numeral 10 designates a drill bit which is illustrated as the usual rock bit type having conical cutters 11 mounted thereon. The bit may be constructed in any suitable manner and includes body sections A, with each of the sections A having an inwardly directed journal shaft or pin 12 disposed at its lower portion.

The present invention relates to the mounting of each cutter 11 upon its journal shaft or pin 12 and as is clearly shown in Figure 2, each cutter is provided with a bore having its major portion 13 cylindrical and having its inner end generally tapered or conical as indicated at 14. Between the cylindrical portion 13 of the bore and the conical or tapered portion the inner wall of the cutter is formed with an annular recess or groove 15 which is preferably generally curved in cross-section. The formation of the recess 15 provides an internal annular shoulder 16 at the inner end of the cylindrical section 13 of the bore.

The journal pin or shaft 12 is generally cylindrical and the outer diameter of the shaft is such that said shaft has a sliding or rotatable fit within the cylindrical section 13 of the bore of the cutter 11. An axial passage 12a may extend through the pin or shaft. The outer end of the shaft is conical or tapered in shape as indicated at 17 and this conical end is adapted to seat within the conical or tapered portion 14 of the cutter bore. The length of the tapered or conical surface 17 of the shaft is such that when the cutter is mounted on said shaft with said conical portion engaging the taper 14 of the bore of the cutter, an annular space 18 is formed by the recess 15 and surrounds a portion of said shaft.

In mounting the cutter and carrying out the present invention an annular area B of the cylindrical shaft which is that area adjacent the con-

ical or tapered end of the shaft is heated by any suitable heating means. Heat induction equipment may be utilized to localize the heating to the area B which is that area of the shaft which will be located opposite the annular space 18 formed by the recess 15 within the bore of the cutter. After the portion B of the shaft has been heated to the desired degree, the cutter is placed in position on the shaft as illustrated in Figure 3, and as has been stated, this locates the heated area B opposite the annular space 18 which is formed within the cutter. The cutter 11 is then supported in a suitable base or support C and a suitable force is applied to the section A by any suitable means, such force being in the direction of the arrows in Figure 4 which is axially of the shaft or pin 12 and of the cutter 11. The force may be applied by any suitable means such as a pressure ram or by a pneumatic hammering tool and the application of force to the section A will result in an upsetting of the heated area B of the shaft, whereby the material in this heated area is deformed to flow into the annular space 18 provided in the wall of the cutter 11. It is noted that when the cutter is first mounted on the shaft as illustrated in Figure 2, the inner end surface of the cutter is spaced a desired distance from the annular bearing surface 19 provided on the section A and this space allows some movement of the section A inwardly of the cutter to permit the upsetting of the area B when pressure is applied to the section as shown in Figure 4.

It will be evident that the heated area B of the shaft will be upset or deformed radially outwardly into the annular space or groove 18 and this upsetting will provide an integral annular rib or projection 20 on the shaft which such projection generally conforming to the cross-sectional curvature of the annular space 18. If desired, the cutter 11 may be rotated on the journal pin while the upsetting of the area B is being accomplished and such rotation will preserve the alignment of the cutter relative to the shaft and will at the same time burnish the bearing surfaces between the cutter and projection. The original spacing between the inner end surface of the cutter 11 and the bearing surface 19 is such that when the heated area B of the shaft has been displaced into the annular space 18 formed by the recess 15, the bearing surface 19 will have the desired running clearance with respect to the inner end surface of the cutter.

The deformation of a portion of the shaft 12 to provide the annular projection or rib rotatably mounts the cutter on the shaft 12 and outward displacement of the cutter from said shaft is prevented. It may be desirable to quench the heated surface B after deformation and in such instance a suitable quenching liquid may be directed to the offset or projection 20 through the axial bore 12a in the journal pin. The axial bore 12a may also be utilized to introduce a lapping or lubricating compound to the bearing surfaces between the cutter and pin 12 whereby said surfaces may be lapped or lubricated by rotating the cutter on said pin.

The mounting is extremely simple since it is only necessary to heat an annular area of the shaft and then apply sufficient force to deform said heated area into the annular space or groove 18 formed within the wall of the cutter. The cross-sectional curvature or shape of the space 18, together with the inclined or tapered coacting surfaces 14 and 17 of the cutter and shaft end, respectively, provide an amplified bearing sur-

face upon which the cutter 11 may rotate. The mounting is extremely rugged, whereby extreme axial thrusts or impacts will not damage the mounting thus making the bit adaptable for efficient operation in hard formations under relatively slow rotative speeds. It is, of course, evident that the size and shape of the annular space 18 which is formed in the wall of the bore of the cutter 11 by the annular recess 15 is subject to variation and it is the size of this space which will determine the amount of deformation of the shaft 12 which will occur to form the annular projection 20 upon the application of force. Thus, any size or shape of annular projection or enlargement as determined by the size and shape of the space 18 may be formed on the shaft. By properly controlling the initial space between the inner end surface of the cutter 11 and the bearing surface 19 of the section A with respect to the size or area of the annular space 18 it is possible to locate the end surface of the cutter 11 in any desired spaced relationship to the surface 19 when the upsetting of the shaft is complete.

From the foregoing it will be seen that this invention is one well adapted to attain all of the ends and objects hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

Having described the invention, I claim:

1. The method of mounting a drill bit cutter having a bore upon a shaft which includes, forming an annular recess in the bore of said cutter, heating a portion of the shaft in an annular path spaced from the end of the shaft, positioning said cutter on the shaft to dispose the heated portion of said shaft opposite the annular recess, and deforming the heated portion of the shaft into said annular recess, whereby an annular integral enlargement is formed on the shaft which coacts with the recess to rotatably mount the cutter on the shaft.

2. The method of mounting a cutter having a bore upon a shaft which includes, forming an annular recess in the bore of said cutter, heating a portion of the shaft in an annular path spaced from the end of the shaft, positioning said cutter on the shaft to dispose the heated portion of said shaft opposite the annular recess, and deforming the heated portion of the shaft into said annular recess by applying a force along an axial line to the shaft and cutter whereby an annular integral enlargement is formed on the shaft which coacts with the recess to rotatably mount the cutter on the shaft.

3. The method of mounting a cone-type drill cutter upon the shaft of a drill bit which includes, forming an annular recess in the wall of the bore of said cutter, heating a portion of the shaft in an annular path spaced from the end of the shaft, positioning the shaft within the bore of the cutter to locate the heated portion opposite the annular recess, and then deforming the heated portion of the shaft into said recess to rotatably connect the cutter to the shaft.

4. The method of mounting a cone-type drill cutter upon the shaft of a drill bit which includes, forming an annular recess in the wall of the bore of said cutter, heating a portion of the shaft in an annular path spaced from the end of the 5 shaft, positioning the shaft within the bore of the cutter to locate the heated portion opposite the annular recess, and then applying a force along an axial line to the shaft and cutter to urge the parts together and thereby deform the 10 heated portion of the shaft into said recess to rotatably connect the cutter to the shaft.
